UNITED STATES PATENT OFFICE.

OMAR A. WHEELER, OF PORTLAND, OREGON, ASSIGNEE, BY DIRECT AND MESNE ASSIGNMENTS, TO WHEELER AUTOMATIC MACHINE CO., A CORPORATION OF OREGON.

THREAD-CUTTER.

1,197,319.

Specification of Letters Patent. Patented Sept. 5, 1916.

Original application filed September 10, 1912, Serial No. 719,656. Divided and this application filed September 11, 1913, Serial No. 789,292. Renewed February 11, 1918. Serial No. 77,806.

To all whom it may concern:

Be it known that I, OMAR A. WHEELER, a citizen of the United States, residing at Portland, in the county of Multnomah and State of Oregon, have invented certain new and useful Improvements in Thread-Cutters, of which the following is a specification:—

The present invention relates to thread cutters, and has for its object to provide a thread cutter adapted for use upon sewing machines and which will automatically grasp and sever the thread at predetermined intervals.

15 The subject matter of the invention was divided out of my application No. 719,656 for automatic sewing machines, filed September 10, 1912.

20 The object sought by this invention is accomplished by means of the structure shown in the accompanying drawing—in which—

Figure 1 is a plan view of the needle plate and thread cutting mechanism, showing connections with the operative parts. Fig. 2 is a perspective elevational view showing the needle plate and cutting jaw. Fig. 3 is an end view showing the thread cutter, with needle in operative position. Fig. 4 is a front elevation of Fig. 1.

30 Describing the drawing in detail, 1 represents a table or support, to which a base member 6 carrying the thread cutter, is secured. Rising from the base at each side, is a stud 1^a on the upper ends of which is carried a needle plate 3 which projects to the rear of the studs. In the longitudinal center of the upper face of this plate is formed a groove 23 in the median portion of which is a converging slot 3^a leading 40 to a central aperture 4 adapted to receive the needle 4^a.

In the upper ends of the studs are journaled the hollow shafts 2 and 2^a respectively, the latter being provided with a 45 tongue 7 which engages in the slot 5 in the former. A bolt 2^b passes through said shafts, and by means of the nut 14 adjustably holds them in position. On the outer portion of each shaft is formed an arm 8 which has at its outer end a right angularly 50 formed cutting jaw 9, rising slightly to the rear of the groove 3^a; and depending from the rear end of said arm, is an arm 8^a, to one of which is pivoted upon the pin 12^a

the forwardly projecting bar 13. Intermediate each of the jaws 9 and its respective end of the needle plate is an oppositely disposed coacting jaw 10, pivotally secured to the angular portion of the jaw 9 upon the pin 12. Extending rearwardly from the lower end of each of said jaws 10 is an arm 10^b having in its end a slot 10^a each adapted to engage over its respective pin 11 fixed in the end of the needle plate, approximately in a horizontal plane with the hollow shafts, so that the jaws will stand open when in down position. By means of this structure, any oscillation of the arm 8^a will produce a corresponding movement in the arm 8, which will cause each pair of jaws 70 to rise above its respective end of the needle plate, one member of each pair rising at each side of the thread groove 23; and in this upward movement the jaws will swing relatively on their respective pivots, closing 75 together as they rise and thereby severing the thread which will lie between them.

This thread cutting device is adapted for use upon a traveling sewing machine which reciprocates upon a machine base sewing in both directions. It will be understood that the thread will extend rearwardly from the needle plate, with reference to the direction in which the sewing machine is advancing. It is therefore essential that a pair of shears 85 be mounted at each end of the needle plate so that a pair of shears will be positioned at the rear end thereof in position to receive and cut the thread at the limit of its travel, after the article being sewed has moved past 90 the edge of the needle plate. This device being adapted for use upon a power driven machine is provided with means whereby it may be mechanically operated. To this end I have provided a rightangled lever 16, 95 pivotally secured upon the table 1 by means of screw 15 through the terminal of one arm. Extending from the angular portion of the lever, in line with said pivoted arm, is a projection carrying a journal 20, upon 100 which is mounted the outer end of bar 13. Within a slot 19 in the lower portion of said extension is secured a spring 21 the outer end of which bears against the stop 24 fixed in the table 1. In the extremity of 105 the other arm of said lever 16 is mounted a roller 17 against which bears the beveled surface of the arm 18, which is carried by

the machine frame or otherwise suitably actuated. By the shifting of the lever the bar 18 will be thrust forward, causing the jaws to rise and close upon the thread above them. After the arm 18 passes the roll 17, the spring 21 will restore the lever 16 and consequently return the jaws to their lower limit. By constructing the hollow shaft in sections it is possible to adjust them upon the jaws and thus hold the latter at the desired degree of tension.

Having now described my invention, what I claim is—

1. In a sewing machine, a thread cutter comprising a base plate, studs rising therefrom, a needle plate disposed parallel with the base at the upper ends of the studs, a bell rock shaft mounted in said studs, a bell crank having one member of a pair of shears standing upright from the terminal of one arm thereof adjacent the needle plate fixed upon each end of said shaft, a coacting jaw pivotally secured to each of the first mentioned jaws, and means for preserving it in working relation thereto, as the former is shifted with the rocking of said shaft.

2. In a sewing machine, a thread cutter comprising a base plate, studs rising therefrom, a needle plate disposed parallel with

the base at the upper ends of the studs, a bell rock shaft mounted in said studs, a bell crank having one member of a pair of shears standing upright from the terminal of one arm thereof adjacent the needle plate fixed upon each end of said shaft, a coacting jaw pivotally secured to each of the first mentioned jaws, means for preserving it in working relation thereto, as the former is shifted with the rocking of said shaft, and means for longitudinally adjusting said shaft to adjust the members of each pair of jaws to each other.

3. In a sewing machine, a thread cutter comprising a base, studs rising therefrom, a needle plate disposed parallel with the base at the upper ends of the studs, a rock-shaft mounted in said studs, a pair of shears carried in upright position by said shaft at the edge of said needle plate, and means for preserving the members of said shears in working relation as they are operated by the rocking of said shaft.

In testimony whereof I affix my signature in the presence of two witnesses.

OMAR A. WHEELER.
